UNITED STATES PATENT OFFICE

HERMAN B. SMITH, OF PLAINFIELD, NEW JERSEY, ASSIGNOR TO THE BABCOCK & WILCOX COMPANY, OF BAYONNE, NEW JERSEY, A CORPORATION OF NEW JERSEY

STEAM BOILER

Application filed January 21, 1926. Serial No. 82,696.

My present invention relates to steam boilers, and particularly to boilers adapted for use with waste gases which are heavily dust laden, and will be best understood from the following description and the annexed drawing which shows a longitudinal sectional elevation of an illustrative form embodying my invention.

In the illustrative embodiment, there are three upper steam and water drums 10, 11 and 12 and two lower water drums 13 and 14. The upper steam and water drums are spaced apart and are connected by steam circulators 15, 16 and water circulators 17, 18. The lower drums 13 and 14 may be connected by a row of circulators 14'.

The lower water drum 13 is positioned out of vertical alinement with either the front drum or the middle drum 11 and beneath the space between these two upper drums. Similarly, the lower drum 14 is positioned out of vertical alinement with either the middle drum 11 or the rear drum 12 and beneath the space between these two drums.

A bank of tubes 19 have their upper ends connected to the drum 10 in the usual manner, so as to enter radially therein, the tubes 19 being substantially straight and vertical for the major portion of their length, being bent at their lower ends and entered radially into the drum 13.

A row 19' of the front bank of tubes 19 is separated from the main bank to provide a superheater space in which is positioned a superheater having U-tubes 20 extending horizontally into this space, the U-tubes having their legs connected respectively with an inlet header 21 and an outlet header 22 preferably located outside of the side wall of the boiler setting. A pipe 23 connects the rear steam and water drum with the inlet header 21.

The middle steam and water drum 11 is connected with the front lower drum 13 by a bank of tubes 24, these tubes being straight and vertical for the major portion of their length with their ends bent to enter each of the drums radially.

The rear steam and water drum 12 is connected to the rear lower drum 14 by a bank

of tubes 25, these tubes also being straight and vertical for the major portion of their length with their ends bent to enter the respective drums radially. A row 25' of the rear bank is spaced from the main bank.

The front wall 26 of the boiler setting extends vertically along the straight portions of the tubes 19 and a baffle 27 is connected to the tubes 19', this baffle 27 and the front wall 26 forming a vertical flue through which extends the front bank of tubes 19. The baffle 27 is spaced from the drum 10, so that gases flowing upward in this vertical flue, can pass over the baffle between the tubes 19' into the bank of tubes 24, this bank being positioned in a vertical flue formed by the baffle 27 and a baffle 28 supported on the tubes 25'. The baffle 28 does not extend to the lower drum 14, so that the gases flowing downward in this middle flue or pass will flow into the rear bank of tubes 25 beneath the lower end of the baffle 28 between the tubes 25'. At the rear of the bank 25 is a wall 29 forming with the baffle 28, a flue in which is positioned the tubes 25. The gases flowing upward in this flue or pass are directed over the top of the wall 29 into an economizer 30, over the tubes of which the gases flow downward to the gas outlet 31. The economizer 30 is made up of a plurality of vertical headers on each side of the setting, these headers being nipped end to end and the lowermost vertical header being connected to a horizontal header 32 through which the feed water enters to flow upward in each of the vertical headers, passing back and forth across the flue through the economizer tubes until the upper header 33 is reached, from which the water passes through any appropriate piping into the boiler, preferably into the rear steam and water drum 12.

The boiler described above is particularly adapted for use with gases from industrial furnaces, such as cement kilns and the like, and I have illustrated an arrangement by which waste gases from cement kilns may be supplied to the boiler. In the drawing, 34 represents such an external source of waste gases, for example, the end of a cement kiln, of which there may be as many as desired, delivering gases to a common flue 35, from

which flue the gases pass through the duct 36 controlled by a damper 37 into a passage 38 which is directly below the vertical flue formed by the front wall 26 and the baffle. 5 Consequently the gases flow vertically upward into this vertical flue, past the drum 13, entering the bank of tubes 19 through the lower bent portions thereof. The gases, after flowing over the tubes 19, pass into the middle 10 and rear passes as described above, and finally through the economizer to the gas outlet 31. Auxiliary baffles 39 are provided in the respective passes to direct the gases into the respective banks of tubes, these auxiliary baffles 15 preferably being made of metal and being inclined away from the tubes toward the wall or baffle with which they cooperate. The baffle 39' between the first and second passes may be made horizontal, as shown.

20 A bridge wall 40 is positioned beneath the drum 13 and any suitable gas seal 41 is provided between the drum 13 and the wall 40. Beneath the front vertical flue and beneath the gas inlet 38 is a dust hopper 42 and beneath the middle and rear passes of the boiler 25 is a dust hopper 43. A dust hopper 44 may also be provided beneath the economizer.

It will be understood that the boiler which I have provided is arranged so that the dust 30 settling from the heating gases will find little or no lodgment on the heating surfaces, and particularly on the lower drums 13 and 14. For instance, in the first pass, as the dust settles out of the gases, it will fall downward 35 through the front pass or flue through the lower bent portions of the tubes 19 into the hopper 42, which would not be the case if the drum 13 were located beneath the drum 10, so that the tubes 19 would not be bent sharply 40 to the right in the figure as is done in my preferred form. Similarly, the drums 13 and 14 are positioned with respect to the middle and rear passes, so that the dust carried downward in the middle pass and falling out of 45 the gases in the rear pass, can drop into the hopper 43 without finding any substantial lodgment on the drums 13 and 14.

By sloping the auxiliary baffles 39, as shown, any dust collecting thereon will slide 50 down into the respective passes and from thence into the hoppers below. It will also be noted that in my arrangement, the boiler can be, and preferably will be supported from the upper steam and water drums, leaving 55 the lower drums 13 and 14 free to move in accordance with the expansion and contraction of the several water tubes, and yet only one gas seal is needed to prevent short-circuiting of the gases by reason of such movement. 60 Furthermore, by forming the wall 29 of plates, the economizer can be incorporated in a single setting with the boiler and, indeed, can be suspended with the boiler. By positioning the superheater in the manner shown, 65 the superheater headers are removed from

the passes so that dust cannot accumulate thereon.

It will also be noted that I have shown 70 five rows of tubes in the front bank, seven rows in the middle bank and seven rows in the rear bank, the tubes 19' and 25' being disregarded in the foregoing statement. By this arrangement of tubes the total heat absorption in the second and third banks is greater than if the number were the same as 75 in the first bank; that is, as the gases progressively are lowered in temperature the amount of surface furnished for the absorption of heat from such gases is progressively increased.

80 I claim:

1. A steam boiler having a vertical flue, a steam and water drum at the top of said flue, a water drum at the bottom of said flue and at one side thereof, a bank of tubes connected to the upper drum and extending vertically in said flue for the major portion of their length and having their lower ends bent and connected to said lower drum, an external source of hot gases, and a gas inlet connecting said source to the bottom of said flue, and means to direct the hot gases from the inlet into the bank from beneath the bent 85 portions of the tubes.

2. A steam boiler having a vertical flue, a steam and water drum at the top of said flue, a water drum at the bottom of said flue and at one side thereof, a bank of tubes connected to the upper drum and extending vertically in said flue for the major portion of their length and having their lower ends bent and connected to said lower drum, a hot gas inlet 90 connected to the bottom of said flue to direct the hot gases into the bank from beneath the bent portions of the tubes, at least one of the rows of tubes in said bank being separated from the main bank to form a superheater chamber, and a superheater in said chamber.

3. A steam boiler having a vertical flue, a steam and water drum at the top of said flue, a water drum at the bottom of said flue and at one side thereof, a bank of tubes connected to the upper drum and extending vertically in said flue for the major portion of their length and having their lower ends bent and connected to said lower drum, a hot gas inlet 110 connected to the bottom of said flue to direct the hot gases into the bank from beneath the bent portions of the tubes, at least one of the rows of tubes in said bank being separated from the main bank to form a superheater chamber, and a superheater in said chamber, said superheater having vertically disposed 115 inlet and outlet headers and tubes extending across said flue and connecting said headers.

4. A steam boiler having two upper steam and water drums spaced apart and a lower water drum positioned beneath the space between the upper drums, a bank of tubes con- 120

- necting each upper drum and the lower drum, a boiler wall and a baffle between the banks defining a vertical flue with the front bank of tubes in said flue, the tubes in said front bank being straight and vertical for the major portion of their length and bent at their lower ends, an external source of hot gases and a gas inlet connecting said source to the bottom of said flue, and means to direct the hot gases from the inlet into the bank from beneath the bent portions of the tubes, the top of said baffle being spaced from the drums to permit the gases to flow from the first bank into the second bank. 5
- 10 5. A steam boiler having a vertical flue, a steam and water drum at the top of said flue, a water drum at the bottom of said flue and at one side thereof, a bank of tubes connected to the upper drum and extending vertically in said flue for the major portion of their length and having their lower ends bent and connected to said lower drum, a hot gas inlet connected to the bottom of said flue to direct the hot gases into the bank from beneath the bent portions of the tubes, and auxiliary baffles between the outside rows of tubes in said bank and the walls of the flue and inclined upward from the tubes to the walls of the flue. 20
- 15 6. A steam boiler having a vertical flue, a steam and water drum at the top of said flue, a water drum at the bottom of said flue and at one side thereof, a bank of tubes connected to the upper drum and extending vertically in said flue for the major portion of their length and having their lower ends bent and connected to said lower drum, a hot gas inlet connected to the bottom of said flue to direct the hot gases into the bank from beneath the bent portions of the tubes, and a dust hopper beneath said vertical flue and said hot gas inlet. 25
- 20 7. A steam boiler having three upper steam and water drums spaced apart and connected by circulators, two lower water drums connected by circulators and spaced apart with one of said lower drums positioned beneath the space between the front and the middle upper drums and the other lower drum positioned beneath the space between the middle upper drum and the rear upper drum, banks of tubes connecting the front and middle upper drums to the front lower drum, a bank of tubes connecting the rear upper drum and the rear lower drum, a boiler setting and baffles between the banks to form three vertical flues each with a bank of tubes therein, a hot gas inlet connected to the bottom of the flue containing the front bank of tubes and the baffles being arranged to permit the gases to flow from the top of the front flue into the middle flue, and from the bottom of the middle flue into the rear flue, the major portion of the tubes in each bank being straight and vertical with their 30
- 35 lower ends bent to enter the respective lower drums and each lower drum being positioned at one side of its respective vertical flue. 40
- 45 8. A steam boiler having a vertical flue, a steam and water drum at the top of said flue, a water drum at the bottom of said flue and at one side thereof, a bank of tubes connected to the upper drum and extending vertically in said flue for the major portion of their length and having their lower ends bent and connected to said lower drum, a hot gas inlet adapted to discharge gases into the space beneath said bent portions of the tubes, a wall extending downwardly from said lower drum and adapted to deflect said gases upwardly into said bank, and a dust hopper disposed beneath said space to receive dust discharged from said gases as they are deflected. 50
